CLAIM

The ornamental design for a magnetic retaining clip for call light and TV monitor cable for hospital beds, as shown and described.

DESCRIPTION

FIG. 1 is a top, isometric view of a magnetic retaining clip for call light and TV monitor cable for hospital beds showing my new design, the opposite side being a mirror image.

FIG. 2 is a bottom isometric view thereof, the opposite side being a mirror image.

The broken lines are for illustrative purposes only and form no part of the claimed design.

FIG. 1

FIG. 2
